UNITED STATES PATENT OFFICE.

JAMES MILLEN, OF MALDEN, MASSACHUSETTS.

DESIGN FOR AN ESCUTCHEON PLATE FOR A DIAL MECHANISM.

Application filed May 3, 1929. Serial No. 31,092. Term of patent 7 years.

To all whom it may concern:

Be it known that I, JAMES MILLEN, a citizen of the United States, and a resident of Malden, in the county of Middlesex and State of Massachusetts, have invented a new, original, and ornamental Design for an Escutcheon Plate for a Dial Mechanism, of which the following description, in connection with the accompanying drawings, is a specification.

Referring to the drawing which forms a part of my application:—

Figure 1 is a front elevation of my new design for an escutcheon plate for a dial mechanism; and

Fig. 2 is a side elevation of the device illustrated by Figure 1.

I claim:

The ornamental design for an escutcheon plate for a dial mechanism, as shown.

In testimony whereof, I have signed my name to this specification.

JAMES MILLEN.
